UNITED STATES PATENT OFFICE.

LOUIS H. HATFIELD, OF NEWARK, OHIO.

DRAFT DEVICE AND FLUE-CLEANER.

1,177,515.

Specification of Letters Patent. Patented Mar. 28, 1916.

Application filed March 20, 1915. Serial No. 15,947.

To all whom it may concern:

Be it known that I, LOUIS H. HATFIELD, a citizen of the United States, residing at Newark, in the county of Licking and State 5 of Ohio, have invented new and useful Improvements in Draft Devices and Flue-Cleaners, of which the following is a specification.

This invention relates to draft devices and 10 flue cleaning appliances for steam boilers.

The invention has for its object to produce a device of simple and improved construction whereby exhaust steam may be utilized for the purpose of increasing the draft in 15 boiler furnaces and at the same time keep the flues and the smoke box clean and free from accumulations of soot and ashes.

A further object of the invention is to produce a device of the character described 20 which will be simple in construction, efficient in operation, and which may be easily and quickly installed in ordinary types of boilers.

With these and other ends in view which 25 will readily appear as the nature of the invention is better understood, the same consists in the improved construction and novel arrangement and combination of parts which will be hereinafter fully described 30 and particularly pointed out in the claim.

In the accompanying drawing has been 35 illustrated a simple and preferred form of the invention, it being, however, understood that no limitation is necessarily made to the precise structural details therein exhibited, but that changes, alterations and modifications within the scope of the claim may be resorted to when desired.

In the drawing—Figure 1 is a sectional 40 view taken longitudinally through a portion of a steam boiler equipped with the invention. Fig. 2 is a transverse sectional view taken on the line 2—2 in Fig. 1.

Corresponding parts in both figures of the 45 drawing are denoted by like characters of reference.

The boiler casing is shown at 15, and the flues are shown at 16, said flues opening into

the smoke box 17 with which the lower end of the smoke stack 18 communicates. Within 50 the smoke box is arranged an inverted funnel 19, the nozzle of which, 20, extends upwardly in the direction of the smoke stack. The bell of the funnel 19 is supported by means of legs or props 21 whereby it is elevated from the floor of the smoke box, the lower end portion of said bell being curved and concentric with the curvature of the smoke box so as to be equally spaced from the bottom portion and said smoke box. A 60 pipe or duct 22 serves to convey the exhaust steam from the cylinders, not shown, said pipe being guided within the smoke box below the bell of the funnel 19 and provided with a discharge nozzle 23 which extends upwardly within the bell to discharge the 65 steam into the nozzle of the funnel.

24 designates the manhole cover of the smoke box.

The steam pipe 22 may be provided with 70 a valve 24'.

When the manhole cover is closed and exhaust steam is admitted through the pipe 22 and nozzle 23, a partial vacuum will be 75 created within the bell of the funnel, thereby producing a suction whereby the soot and ashes in the bottom of the smoke box, as well as that contained in the flues 16, will be forced to travel through the bell of the funnel 19 and upwardly through the nozzle 20 80 into the smoke stack through which the obstructions will be ejected.

The curvature of the lower end portion of the funnel 19 enables it to be placed closely adjacent to the bottom portion of the smoke 85 box, covering a large area and thereby rendering the operation of the device more efficient.

Having thus described the invention, what is claimed as new, is— 90

In combination with a steam boiler having a smoke box, a nozzle disposed in the smoke box, and an exhaust steam pipe connected with said nozzle, of an inverted funnel surrounding said nozzle within the smoke box 95 and having its bottom peripheral edge curved

concentrically with the curvature of the peripheral wall of the smoke box adjacent said nozzle, and supporting legs carried by said funnel and contacting with the bottom peripheral wall of the smoke chamber adjacent said nozzle whereby, the bottom peripheral edge of the funnel is held in spaced relation with the bottom of the smoke box

and the neck of the funnel in spaced relation with the mouth of the nozzle.

10

In testimony whereof I affix my signature in presence of two witnesses.

LOUIS H. HATFIELD.
